United States Patent Office.

ANDREW BENNETT, OF BROOKLYN, NEW YORK.

Letters Patent No. 91,596, dated June 22, 1869.

IMPROVEMENT IN RANGE-BOILERS.

The Schedule referred to in these Letters Patent and making part of the same.

To all whom it may concern:

Be it known that I, ANDREW BENNETT, of Brooklyn, in the county of Kings, and State of New York, have invented a new and useful Improvement in Range-Boilers; and I do hereby declare that the following is a full, clear, and exact description thereof, which will enable others skilled in the art to make and use the same, reference being had to the accompanying drawing, forming part of this specification.

The figure is a vertical longitudinal section of the upper part of my improved range-boiler.

My invention has for its object to furnish an improved range-boiler, the dome-top of which shall be securely and strongly connected to the body of said boiler; and

It consists in the construction and combination of the dome-top and cylindrical body of the boiler with each other, in the manner hereinafter more fully described.

A is the dome-top of the boiler, which is constructed in the ordinary manner, except that it is beaded around its lower edge, as shown in the figure, that is to say, with a larger central bead, having a smaller bead upon each side.

B is the body of the boiler, which is made cylindrical in form, in the usual manner.

Around the upper edge of the body B is formed a row of tongues, b', which are cut and struck up out of the solid metal of the body B, as shown in the figure.

The upper edge of the body B is also slightly turned outward, as shown in the figure, to bear against the inner surface of the top A.

In forming the boiler, the upper end of the body B is pushed into the top A, until the tongues b drop into the groove of the central bead of the top A.

By this construction, as the solder is melted, it flows through the grooves of the beading a', surrounding the tongues b', which thus become firmly embedded in the solder, the upper edge of the body B preventing the flowing out of the said solder, and confining it to the grooves of the said beading, thus strongly securing the top and body of the boiler to each other.

Having thus described my invention,

What I claim as new, and desire to secure by Letters Patent, is—

Securing the top A and body B of the boiler to each other, by means of the beading a', formed around the lower edge of said top, and the tongues b' cut out and struck up from the solid metal of the said body B, to give the solder a firm hold upon both of said parts, substantially as herein shown and described.

The above specification of my invention signed by me, this 6th day of May, 1869.

ANDREW BENNETT.
